UNITED STATES PATENT OFFICE.

EDMUND F. HEARD, OF ELIZABETH CITY COUNTY, AND MAYO M. FITZ HUGH, OF NEWPORT NEWS, VIRGINIA, ASSIGNEES TO NEWPORT NEWS SHIPBUILDING & DRY DOCK COMPANY, OF NEWPORT NEWS, VIRGINIA, A CORPORATION OF VIRGINIA.

HEAD FOR LATHES.

Application filed November 13, 1924. Serial No. 749,680.

Our invention relates to a head for lathes and has for its object the provision of an improved device of this character. More particularly, it relates to a combined driving and steadyng head for lathes, polishing machines, grinders and the like equipped with a central driving head through which the turning effort is transmitted to the piece being operated upon, whereby said piece, which may be an axle, shaft, bar or the like, is driven and steadied, while being turned, burnished, polished, ground or otherwise operated upon.

Another object of our invention is to provide a device of the character described of rugged and simple construction, which may be readily and easily adjusted by the operator, and which is efficient in operation.

A further object of our invention is to eliminate the use of a dog for driving the piece being worked upon, to prevent said piece from springing thereby avoiding chattering, and to keep said piece true or straight during the operation.

Our invention will be better understood from the following description taken in connection with the accompanying drawings and its scope will be pointed out in the appended claims.

In the drawings illustrating our invention:

Fig. 1 is a side elevation of the central portion of a double type of lathe embodying our invention,

Fig. 2 is an end view of our improved driving and steadyng head,

Fig. 3 is a section taken on the line 3—3 of Fig. 2,

Fig. 4 is a detailed view of a jaw and its operating cam, and

Fig. 5 is a detailed view of a modified type of jaw.

Referring to the drawings in which 1 indicates the bed of a well-known double-end lathe, polishing machine or grinder, having a face plate 2, and gear 3 bearing against the frame 4, which gear is driven through a pinion 3' from a suitable power source in a well understood manner. Our improved driving and steadyng head, indicated at 5 in Fig. 1, is secured to face plate 2 by a suitable number of bolts 6, and driven therewith.

As shown in Figs. 2 and 3, our combined

driving and steadyng head 5 comprises a 55 metallic frame or annular member 7. In the preferred form, the annular member 7 is a separate unit, although if desired, it could be made integral with the face plate 2.

In designing a machine with a central 60 driving head, as mentioned hereinbefore, in order to secure the maximum stiffness and rigidity of the machine, it is desirable to keep the center about which the work rotates as near the bed of the lathe as possible, which 65 result is attained by our invention. On its exterior surface, the annular member 7 is provided with a plurality of hinged blocks, 70 two of which are shown at 8 and 9, pivoted on pins 10 and 11 respectively, which pins 75 are supported in lugs 12, 13 and 14, 15 respectively formed on said annular member. The blocks 8 and 9 are provided with steadyng 80 rests 16 and 17 respectively. The annular member 7 is also provided with a block 18, pivoted on a pin 19, supported in lugs 20, 21, formed on said annular member, said block 18 having a toothed or serrated driving member 22 as will be more fully described hereinafter. The axes of pins 10, 85 11 and 19 are tangent or approximately tangent to a circle drawn with its center at the center of the piece being worked upon indicated by the broken circle A and the blocks 8, 9 and 18 are hinged on said pins respectively 85 so that their free ends, carrying the rests 16 and 17 and driving member 22 respectively, may swing outward from the face plate 2 and away from the center of said annular member, thus providing a relatively 90 large opening for the passage of axles, shafts, and the like into and out of the machine.

While we do not limit ourselves to any particular number of blocks 8, 9 and 18, three of such blocks are shown, which are 95 arranged equidistantly from each other.

The steadyng rests 16 and 17, are provided at their free ends with similar pins 23 and 24 respectively. The outer ends of said pins bear against the piece being turned, indicated at A, and their inner ends engage similar cams 25 and 26, one of which is shown in detail in Fig. 4. The pins 23 and 24 may be provided with shoulders 27 and 28 respectively, and blocks 16 and 17 may be cut away as shown to receive springs 29 and 30 respectively, which arrangement is best shown in Fig. 3. By this arrangement,

the pins 23 and 24 may be locked in the desired position by rotation of the cams 25 and 26 in a manner readily understood. If desired, the steadyng rests 16, 17 may be threaded internally and the pins 23, 24 provided with cooperating external threads, as indicated in Fig. 5. In this form, the ends of the pins are provided with a swiveled block 31, and adjustment may be made by means of a nut 32.

The toothed or serrated driving member 22 is pivoted on a pin 33 parallel with the axis of the piece A. The outer toothed portion 34 of member 22 is curved and in the form of a segment of a circle, although it may assume other forms, such as a series of intersecting circles, or a series of points connected by straight or curved surfaces, the gripping surface 34, so formed, not being equidistant from the center 33 about which the member 22 rotates. While we have shown the outer gripping surface of member 22 as toothed, it is of course understood that this surface may be plain or assume other forms. Thus, if the driving member or dog 22 is rotated about its center 33 in a direction opposite from that in which the axle or shaft A is rotated when being turned, a portion of the driving or gripping surface 34 is moved toward the axle or shaft A substantially in a plane transverse to the axis of the shaft, and upon coming in contact with said axle or shaft, it tends to rotate the axle or shaft with the driving head 5. The greater the resistance offered to rotation of the axle or shaft by the cutting, burnishing, grinding or polishing tools, the greater will be the effort or tendency of gripping member 22 to force the axle or shaft A to rotate with the face plate 2.

The blocks 8, 9 and 18 are each provided with a pin 35, best shown in Fig. 3, arranged to engage a stop 36 fixed on annular member 7 when the blocks are swung to their open positions, the open position of block 19 being indicated in broken lines in Fig. 3. In order to retain the rests 16 and 17 and the gripping member 22 in whatever position they are placed, and particularly to prevent their falling into the closed position while the piece A is being placed in the lathe, each of the blocks is provided with a recess 37 on the surface adjacent the annular member 7, adapted to receive a flat spring 38, best illustrated in Fig. 3, although we do not limit ourselves to this particular means for accomplishing this result.

When the annular member 7 is not made integral with face plate 2, to compensate for wear in the centers of the lathe and to permit adjustment to be made in the carrying centers upon which the piece A rotates without loosening or ungripping the driving mechanism, resilient means, preferably rubber washers 39, are placed on each of the

screws 6, intermediate the annular member 7 and face plate 2. Thus a perceptible movement along the axis of the lathe centers of the driving mechanism may be obtained, and the axle or shaft with the entire driving mechanism except face plate itself can be moved in a direction parallel to the line of centers of the lathe.

From the foregoing, it will be seen that we have provided a mechanism in which the points of contact between the piece A being operated upon and the driving head and steadyng rests do not move with respect to each other, and that the turning effort, necessary for driving the piece A is transmitted through the gripping member 22 and pins 23 and 24 of the steadyng rests.

From a consideration of the above description, taken in connection with the drawings, our invention will be apparent without further explanation, and the advantages set forth prior to the detailed description will readily be recognized. We do not wish to be understood as being limited to the details of form or arrangement of parts herein set forth, for various changes may be made by those skilled in the art without departing from the spirit and scope of our invention.

What we claim and desire to secure by United States Letters Patent is:

1. In a machine tool, a combined driving and steadyng device comprising a supporting frame, means for rigidly fixing the same to the rotatable head of the machine tool, a plurality of steadyng rests thereon adapted to permit rotation of the work with respect thereto, a driving element on said frame, adapted to swing laterally with respect to the work and clamp the latter when said work tends to turn with respect to said steadyng rests, and means on said frame connected with said rests and gripping member to permit displacement thereof to inactive positions when the work is removed.

2. In a device of the character described having a central driving head, an annular member on said head having steadyng rests and a gripping member pivoted thereon, arranged to engage the element to be operated upon, whereby the turning effort of said driving head is transmitted to said element by said gripping member, said rests and gripping member being arranged to swing toward and away from the axis of said head, said gripping member being pivotally mounted to swing transversely of said element to increase the force transmitted thereto.

3. In a device of the character described, a combined driving and steadyng head comprising an annular member, a plurality of adjustable inwardly extending steadyng rests pivoted on said member, each of said rests having a slidable pin at their free ends,

- a cam for actuating said pin and resilient means urging said pin against the cam, an inwardly extending gripping element pivoted on said annular member, said rests and gripping element being arranged to swing toward and from the axis of said device, whereby the element to be turned may be supported by and driven through said rests and gripping element.
4. In a device of the character described, a combined driving and steadyng head comprising an annular member, a plurality of inwardly extending steadyng rests pivoted on said member, each of said rests having a 10 slidable pin at their free ends, a cam for actuating said pin and resilient means urging said pin against the cam, an inwardly extending gripping element pivoted on said annular member comprising a member pivoted on an axis parallel with the axis of the element to be turned and having a gripping surface varying with respect to its axis, said rests and gripping element being arranged to swing toward and from the axis of said 15 device, whereby the element to be turned may be supported by and driven through said rests and gripping element.
5. In a device of the character described, a combined driving and steadyng head comprising an annular member, a plurality of inwardly extending steadyng rests pivoted on said member, an inwardly extending gripping element pivoted on said annular member, said rests and gripping element being 20 arranged to swing longitudinally toward and from the axis of said device, said gripping element being pivotally mounted to swing transversely of the axis of the element to be turned and shaped so that when 25 swung from its normal position the distance from its pivot point to the point of contact
- with the work is increased, whereby the element to be turned may be supported by and driven through said rests and gripping element respectively and means limiting the 45 outward movement of said steadyng rests and gripping element.
6. In a machine tool, a combined driving and steadyng head comprising an annular member, a driving head pivotally mounted 50 upon said member, a plurality of steadyng rests pivotally mounted upon said member and comprising radially-adjustable elements adapted to support the work radially and to permit turning of the work with respect thereto, a driving element pivoted to said driving head, and adapted to swing laterally with respect to the work and to contact therewith and clamp the same at various distances from its pivot point on the driving 55 head.
7. In a head for lathes, an annular member through which an element to be operated on is adapted to pass, three members for holding the element in position in the 60 annular member, two of the members being adjustably mounted pins adapted to support the work radially while permitting rotative movement with respect thereto, the third member being a serrated gripping member, 65 each of the members being pivotally mounted on the annular member so as to swing towards a position substantially parallel with the axis of the element and thus to enlarge the space between them to facilitate 70 introduction of the element and the gripping member being pivotally mounted to rotate towards and from the element substantially 75 in a transverse plane.

Signed this 8th day of November, 1924.
